UNITED STATES PATENT OFFICE.

EMIL G. JOHANSON, OF CHICAGO, ILLINOIS.

PRESS.

1,269,186.

Specification of Letters Patent. Patented June 11, 1918.

Application filed December 6, 1917. Serial No. 205,802.

To all whom it may concern:

Be it known that I, EMIL G. JOHANSON, subject of the King of Sweden, residing at Chicago, in the county of Cook and State of Illinois, have invented a certain new and useful Improvement in Presses, of which the following is a full, clear, concise, and exact description.

My invention relates to presses and is of particular service in connection with those presses which are employed in molding plastic material such as molten glass, though the invention is not to be limited to any particular use to which it may be put.

It is one of the objects of my invention to provide means whereby a single press may employ a plurality of forming plungers to which power may be suitably applied to enable the plungers to perform their function.

It is another object of my invention to employ means whereby the work may be automatically fed to the plungers in order to dispense with the manual feeding adjustment hitherto effected by operators.

I will explain my invention more fully by reference to the accompanying drawings showing the preferred embodiment thereof and in which Figure 1 is a view in end elevation, partially in section, of a press constructed in accordance with my invention; Fig. 2 is a view on line 2—2 of Fig. 1; Fig. 3 is a view on line 3—3 of Fig. 1; Fig. 4 is a view of a molding box, with the top and bottom thereof in separated relation, that may be employed in forming glass head-lights; and Fig. 5 illustrates some of the mechanism whereby the molding box may be fed step by step to plungers of the press.

Like parts are indicated by similar characters of reference throughout the different figures.

The press illustrated includes the press base 1 which supports an overhanging upright extension 2. A vertical cylindrical tubular guide 3 depends from the extension 2 and overlies the central portion of the base 1. The plunger head 4 is provided with an upwardly extending vertically semi-tubular projection 5 that is movable up and down in the tubular guide 3. The plunger head 4¹ is also provided with an upwardly extending vertical semi-tubular projection 5¹ that is also movable up and down in the guide 3, the heads 4, 4¹ being movable relatively. The plunger heads 4, 4¹ carry two depend-

ing plungers 6, 7. A lever 8 is connected at one end to the plunger head 4 near the plunger 6. A lever 9 is connected to the other plunger 7 by being pivotally connected at one end to the plunger head 4¹ near the plunger 7. A connecting member 10, which is preferably of U-shape, connects the other ends of the levers 8 and 9, the sides of the U-shaped member 10 being upright and freely passing through openings in the plunger heads 4, 4¹ whereby the member 10 is movable with respect to the plunger heads 4, 4¹. The member 10 is provided with an upwardly extending vertical stem 11 that works within the bore formed by the two semi-tubular projections 5, 5¹ that guide said stem in vertical movement. A third forming plunger 12 is carried by and depends from the member 10. As illustrated, the plungers 6, 7 and 12 are substantially in the same horizontal plane when idle and occupy the same horizontal plane when their working strokes are finished although being adapted to assume different levels with respect to each other during their working strokes in accordance with my invention, as will later more fully appear. Two links 13 and 14 are employed, link 13 being pivotally connected to the lever 8 between the ends of said lever. The link 14 is pivotally connected with the lever 9 between the ends of this lever. I also desirably employ two springs 15 and 16, spring 15 being in actuating connection with link 13 and spring 16 in actuating connection with link 14. Actuating power is applied to the springs 15 and 16 and from these springs to the links and levers 8, 9, 13 and 14 which have been described and in order that this result may be effectively accomplished I desirably rest the lower ends of these springs upon shoulders 13¹, 14¹ formed by reducing the upper ends of the links 13, 14. The upper ends of said springs are engaged by shoulders 17¹, 18¹ formed by reducing the lower ends of the links 17 and 18. The links 17 and 13 are aligned and the reduced ends thereof are surrounded by the spring 15, these reduced ends being in sliding relation. The links 18 and 14 are also aligned and the reduced ends thereof which are in sliding relation are surrounded by the spring 16. The upper ends of the links 17 and 18 are respectively connected with the levers 19 and 20 which are respectively in fixed relation with the seg- 114

mental gears 21 and 22 that are in mesh with each other.

The lever 20 is carried below the link 18 and terminates in an operating handle 23. 5 By applying downward pressure upon the handle 23 the lever 9 is depressed as is obvious and the lever 8 is at the same time depressed owing to the intermeshing gears 21 and 22. The springs 15 and 16 serve yield- 10 ingly to apply actuating power to the levers 8 and 9 and the forming plungers 6, 7 and 12, in their downward movement or working strokes, are free to shift their relative positions in performing their work, a result 15 which is permitted owing to the connection of the levers 8 and 9 by the connecting member 10.

The forming plunger 12, being upon the connecting member 10, there is afforded a 20 third plunger whose position with respect to the other plungers is automatically regulable.

The particular type of press illustrated is one which is adapted to the formation of the 25 front glasses of headlights such as are commonly seen in headlights of automobiles, one such headlight glass being illustrated in section at 24, Fig. 2. In the formation of these headlight glasses there is employed a 30 mold box that includes a mold board 25 having rows of cavities 26 that conform to the shape and design of the headlight glasses that are to be formed by the press. There being preferably three plungers in the press, 35 the cavities 26 are arranged in rows that extend transversely of the board 25, there being three cavities to a row. The cover 27 of the mold box has rows of openings 28 that are in registry with the cavities 26, such registry being assured by means of pins 29 depending from the cover 27 that are receivable in the openings 30 in the board 25.

Each row of cavities 26 and the openings 28 above the same are in alinement with the 45 plungers 6, 7 and 12, there having been placed in each of these cavities just about the quantity of molten glass that is required to make a headlight glass whereafter the handle 23 is depressed to cause the descent 50 of the forming plungers. The masses of molten glass that are initially placed in the cavities are of dissimilar shape so that the plungers will initially have dissimilar engagement therewith but owing to the means 55 set forth the plungers will automatically be shifted to adapt themselves to the masses of molten glass whereby the molten glass will be properly distributed in the various cavities, the plungers assuming the same level 60 when their working stroke is finished, at which time the masses of molten glass are brought to shape. The pressure exerted upon plunger 12 is suitably proportioned with respect to the pressure exerted by each 65 plunger 6, 7 by suitably locating the place

of connection of the links 13 and 14 with the levers 8 and 9, it being thus possible to make the pressure exerted by plunger 12 different from or equal to the pressure exerted by each of the other plungers, as desired. After a row of headlight glass has been formed the mold box is moved forward sufficiently to bring a succeeding row of cavities 26 below said plungers whereafter the operation described is repeated. After 70 headlight glasses have been formed in all of the cavities the mold box is removed from the press whereupon the top and bottom of the mold box may be separated to permit of the removal of the glasses. The means 75 for feeding the mold box step by step beneath the plungers may include an arm 31 moving with the segmental gear 21, the link 32 connected with the outer end of the arm 31, a rocker arm 33 movable upon the shaft 35 80 34, the ratchet wheel 35 in fixed relation to the shaft 34, an actuating pawl 36 in actuating relation to the ratchet wheel 35 and pinions 37 fixed upon the shaft 34 and in mesh with racks 38 that are carried by and depend from the bottom 25 of the mold box. On each downward depression of the handle 23, the pawl 36 is moved into engagement 85 with a fresh tooth of the ratchet wheel 35 and upon each upward movement of the handle 23 the pawl 36 turns the ratchet wheel one step which is sufficient to advance a fresh row of cavities 26 to a position beneath the plungers. The trailing dog 39 holds the ratchet wheel 35 from reverse rotation. The lever 20 and its handle 23 constitute means common to the plungers and the levers connected with the plungers for operating these plungers and levers together, this lever 20 performing its work 90 directly upon some of the parts and indirectly upon other parts through the inter-mediation of the gears 21 and 22. The springs 15, 16 not only serve as a medium through which power is transmitted to the 95 plungers but also aid in effecting upward withdrawing movement of the plungers. 100

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. A press including two relatively movable plungers; a third plunger movable with respect to each of the aforesaid plungers; two levers for effecting operation of the aforesaid plungers, one connected with each of the first aforesaid plungers and both connected with the third plunger; and mechanism for effecting plunger actuating operation of the levers. 125

2. A press including two plungers; a third plunger movable with respect to each of the aforesaid plungers; two levers for effecting operation of the aforesaid plungers, one connected with each of the first aforesaid plungers and both connected with the third plunger; and mechanism for effecting plunger actuating operation of the levers. 20
3. A press including two relatively movable plungers; a third plunger movable with respect to each of the aforesaid plungers; two levers for effecting operation of the aforesaid plungers, one connected with each of the first aforesaid plungers and both connected with the third plunger; two operating levers for operating the aforesaid levers; two intermeshing gears, one connected with each of said operating levers; and links connecting the first mentioned levers with the last mentioned levers. 25
4. A press including two plungers; a third plunger movable with respect to each of the aforesaid plungers; two levers for effecting operation of the aforesaid plungers, one connected with each of the first aforesaid plungers and both connected with the third plunger; two operating levers for operating the aforesaid levers; two intermeshing gears, one connected with each of said operating levers; and links connecting the first mentioned levers with the last mentioned levers. 30

In witness whereof, I hereunto subscribe my name this third day of December, A. D., 1917.

EMIL G. JOHANSON.
